Primary Examiner — Jennifer L Rempfer*Assistant Examiner* — Adrienne Corna(74) *Attorney, Agent, or Firm* — Quarles & Brady LLP(57) **CLAIM**

The ornamental design for a shoe, as shown and described.

DESCRIPTION

FIG. 1 is a top, right, and front perspective view of an ornamental design for a shoe;

FIG. 2 is a left side elevational view of the shoe of FIG. 1; and,

FIG. 3 is a right side elevational view of the shoe of FIG. 1. The dash-dot-dash lines are included for the purpose of illustrating boundary lines and form no part of the claimed design. The dash-dash-dash lines are included for the purpose of illustrating portions of the shoe that form no part of the claimed design.
